UNITED STATES PATENT OFFICE.

LEE F. CHANEY, OF SPRINGFIELD, OHIO.

PRIMING-PUMP FOR EXPLOSIVE-ENGINES.

1,265,881.

Specification of Letters Patent. Patented May 14, 1918.

Application filed October 26, 1915. Serial No. 58,064.

To all whom it may concern:

Be it known that I, LEE F. CHANEY, citizen of the United States, residing at Springfield, in the county of Clark and State of Ohio, 5 have invented certain new and useful Improvements in Priming-Pumps for Explosive-Engines, of which the following is a specification.

My invention relates to pumps and more 10 particularly to priming pumps for explosive engines. The device forming the subject matter hereof is especially designed for feeding fuel in small quantities to the cylinders of an ordinary hydrocarbon engine, but 15 it is also applicable to other purposes.

The object of the invention is to simplify 20 the structure as well as the means and mode of operation of such devices whereby they will not only be cheapened in construction, 25 but will be more efficient in use, positive in action, semi-automatic, and unlikely to get out of repair.

A further object of the invention is to provide 30 an improved form of valve mechanism for such pumps and means for positively locking the inlet valve upon its seat.

With the above primary and other incidental objects in view, as will more fully appear in the specification, the invention 35 consists of the features of construction, the parts and combinations thereof, and the mode of operation, or their equivalents, as hereinafter described and set forth in the claims.

35 Referring to the drawings, Figure 1 is a side elevation illustrating the application of the pump to the dash of an automobile and the supply conduit connection to the fuel reservoir. Fig. 2 is a longitudinal sectional 40 view of the assembled pump. Fig. 3 is a transverse sectional view through the valve head. Fig. 4 is a longitudinal sectional view taken on a plane angular to that of Fig. 2.

45 Like parts are indicated by similar characters of reference throughout the several views.

In the drawings, 1 is the dash of an automobile or motor vehicle of which 2 is a fuel 50 supply reservoir. Rigidly mounted upon the dash 1 is the priming pump 3 forming the subject matter hereof. Leading from the fuel reservoir 2 to the engine carbureter (not shown) is the usual fuel supply conduit 55 4. Extending from the fuel supply conduit 4 to the priming pump 3 is a branch conduit

5 which affords direct communication between the priming pump 3 and the fuel reservoir 2 through which the charge of fuel is drawn to be discharged by the pump 3 60 through the outlet or discharge conduits 6 to the several cylinders of the explosive engine. This charge of fuel is delivered to the several cylinders either through priming cups or through the shells of the spark plug as is 65 now the common practice.

The pump 3 comprises a cylinder 7 having at one end a cap or head 8 screw threaded thereon through which the piston rod, hereafter mentioned, extends. Screw threaded 70 upon the exterior of the cylinder 7 adjacent to the cap or head 8 is a jam nut 9. A convenient and simple method of mounting the pump upon the dash of the vehicle is to introduce the barrel or cylinder of the pump 75 through a suitable opening therein with the jam nut 9 upon one side of said dash and the screw threaded cap or head 8 upon the opposite side. By tightening the jam nut 9 the pump or primer may be securely clamped 80 to the dash. It is obvious that other methods of mounting the pump may be provided or that the pump may be located elsewhere than on the dash of the vehicle. At the opposite end of the barrel or cylinder 7 there 85 is secured a head 10 containing the valve mechanism and hereafter referred to as the valve head. This head 10 is screw threaded or otherwise securely attached to the barrel or cylinder 7. The head 7 is provided with 90 a transverse counterbore 11 forming a seat 12 for a ball valve 13 controlling the inlet orifice of the supply conduit 5. The larger end of the transverse counterbore 11 is securely closed after the insertion of the ball 95 valve 13 by means of a screw plug 14. Intersecting the transverse counterbore 11 is a longitudinally disposed centrally located bore 15 of less diameter than the transverse bore 11 whereby the ball valve 13 is prevented from escaping from the transverse bore 11 into the longitudinal bore 15. Mounted to reciprocate within the valve or cylinder 7 of the pump is a piston comprising a head 16 and a piston rod 17 extending 100 through a central opening in the cap or head 8 and provided at its outer end with an operating rod or handle 18. Surrounding the piston rod 17 and bearing at one end upon the cap or head 8 and at its opposite 110 end upon the piston head 16 or, as shown in Fig. 2, upon an interposed disk or washer 19,

is a helical spring 20 which tends to move the piston toward the valve head 10 and against the tension of which the piston may be moved by manual effort to draw a charge 5 of fuel into the valve or cylinder. Upon its forward side or that side adjacent to the valve head 10 the piston is provided with a projecting stud 21 adapted to extend within the longitudinal bore 15 when the piston is 10 at the limit of its stroke. The stud 21 is inclined or tapered at its extremity and is adapted to engage the ball valve 13 and securely hold said valve upon its seat 12. The construction is such that the movement 15 of the piston under the influence of the spring 20 is limited by the engagement of the stud 21 with the ball valve 13. In the construction shown in Fig. 2 the tapered end of the stud 21 projects into the path of 20 the ball 13 and positively locks said ball in position to close the inlet port of the pump. If the ball valve 13 happens to be slightly off its seat the tapered extremity of the stud 21 will afford a cam-like action which will 25 reseat the valve. While the piston spring 20 serves to move the stud 21 to locking position, it is to be noted in Fig. 2 that the resistance to the unseating of the valve is not dependent upon the tension of the spring but 30 the locking action is due to projection of the stud into the path of the valve 13.

There are also provided, in the valve head 10, a plurality of outlets or discharge ports 22 each connected by a corresponding conduit 35 6 with a cylinder of the engine. Each of these outlets or discharge ports 22 is controlled by a spring pressed ball valve 23 each independent of the other and adapted to open against the tension of the spring 40 24 to permit the escape of the fuel from the pump valve or cylinder as the piston approaches the head 10 under the influence of the spring 20. In practice the conduit 6 and valve 22 are each subjected to alternate suction and compression as the pistons 45 of the engines operate to draw in a charge of fuel and then compress the same. If the independent valves 22 were omitted the compression would escape from one cylinder 50 through its corresponding conduit 6 and port 22 to the pump and thence through another port 22 and corresponding conduit 6 to a second cylinder of the motor. However, the valves 23, one for each outlet or 55 discharge port 22, effectually prevent such loss of compression. On a return stroke of the engine piston to draw in a succeeding charge, the suction transmitted through the conduits 6 might be sufficient to unseat the 60 valves 23 and lift the inlet valve 13 from its seat 12 and so draw liquid fuel into the cylinders through the pump and conduit 6 if the said valve 13 was not securely locked in closed position. However, with the inlet 65 valve 13 held upon its seat 12 by the action

of the pump piston, as shown in the several views, the admission of liquid fuel under the influence of the suction due to the engine piston is effectually prevented.

From the above description it will be apparent that there is thus provided a device of the character described possessing the particular features of advantage before enumerated as desirable, but which obviously is susceptible of modification in its form, proportion, detail construction, or arrangement of parts, without departing from the principle involved or sacrificing any of its advantages.

While in order to comply with the statute the invention has been described in language more or less specific as to certain structural features, it is to be understood that the means and construction herein described comprise but one mode of putting the invention into effect and the invention is therefore claimed broadly in any of its possible forms or modifications within the scope of the appended claims.

Having thus described my invention, I claim:

1. A pump cylinder, a piston therein, a supply conduit connecting the cylinder with a fuel reservoir, an inlet valve controlling the fuel supply, said valve being laterally movable in relation to the direction of movement of the piston, a plurality of outlet ports each connected with an engine cylinder, an independent valve for each outlet port, preventing intercommunication between different engine cylinders through said ports, and a cam extension on the piston adapted to shift the inlet valve laterally and to lock the said valve against movement.

2. A pump comprising a cylinder, a reciprocatory piston therein, a laterally disposed port in said cylinder, a valve therefor movable laterally under the influence of said piston, the construction and arrangement being such that the inlet valve will be locked by the movement of the piston.

3. A pump cylinder inlet and outlet valves, a laterally disposed seat for the inlet valve, a reciprocatory piston and a cam extension on the piston adapted to move the inlet valve toward its lateral seat when said piston approaches the limit of its stroke.

4. In a construction of the character described a cylinder having a laterally disposed port, a reciprocating piston within the cylinder, a valve for said laterally disposed port and a cam member actuated by the movement of the piston, adapted to engage and actuate said valve upon the movement of the piston.

5. In a construction of the character described, a cylinder, and piston therein, a chambered head for the cylinder, a ball valve loosely positioned in said chamber

and movable into and out of the path of the piston, a port in the cylinder head controlled by the valve and a cam member actuated by the movement of the piston to shift said 5 ball valve within the chamber out of the path of the piston.

6. A pump comprising a cylinder, a reciprocating piston therein, inlet and outlet valves, said inlet valve being movable into 10 and out of the path of the piston, and a

cam extension on said piston actuating the inlet valve toward its seat by the movement of the piston.

In testimony whereof I have hereunto set my hand this 20th day of October, A. D. 15 1915.

LEE F. CHANEY.
